CONCRETE SHEET PILING

Alexander George Rotinoff, deceased, late of Kingsway, London, England, by Anne Michael Rotinoff and George Alexander Rotinoff, administrators, South Kensington, England, assignors to West's Rotinoff Piling & Construction Company Limited, London, England

Application November 8, 1934, Serial No. 752,158
In Great Britain November 11, 1933

10 Claims. (Cl. 61—59)

This invention relates to concrete sheet piling and like structures for the formation of watertight walls and coffer-dams and for the carrying of superstructures, and has for its object to provide for the effective connection of adjacent piles to one another without imposing upon the concrete of the piles excessive tension and shearing stresses such as will arise during the pile driving operation and which may cause fracture thereof.

10 The invention comprises the interlocking or connection together of adjacent piles during and if desired after the pile driving or sinking operation by an intermediate part secured to the two adjacent piles by metal tension members passing through the concrete of the said piles at intervals in their length, the said members permitting of longitudinal movement of the intermediate interlocking part relatively to the piles but preventing such movement laterally with relation to the 20 piles.

The invention further comprises the improved methods of and means for interlocking piles as hereinafter described and claimed.

Referring to the accompanying sheet of explanatory drawings:

Figures 1—6 are plan views illustrating nine constructions of sheet pile interlocking means arranged in accordance with this invention.

Figure 7 is a detail view drawn to an enlarged scale of the end of one of the tension members shown in Figures 4 and 7.

Figure 8 is a plan view illustrating the application of the invention to the interconnection of substantial structures in the form of caissons 35 which resemble piles except in respect of their dimensions.

Figures 9 and 10 are an elevation and a perspective view of complete interconnected piles.

In all the figures tension members extend into and through the concrete at intervals in the vertical length of each pile or caisson as shown in Figure 9.

The tension members project from opposite sides of each pile or caisson and the projecting parts are shaped or arranged so that they can take an effective hold upon an intermediate member which is to hold adjacent piles or caissons together while permitting relative longitudinal movement between the piles and intermediate members for the purpose hereinafter more fully specified.

In Figures 1 and 2, the tension members consist of rods or bars *a* extending completely through 55 the concrete of the pile *b* or *b'* and headed at

each end at *d* to enter recesses in the opposite sides of the intermediate member *c* or *c'*.

In Figures 3, 4, 5 and 6, the tension bars are in pairs and may be interconnected by a stirrup piece (as shown at *e* in Figures 4, 5 and 7) adjacent to their ends to hold the bars at the requisite distance apart. The ends *f* of the pairs of tension bars *a*² are turned inwards so that they can take over the sides of the intermediate members *c*², *c*³. The piles are shown at *b*² in Figures 10, 3, 4, and 5, at *b*³ in Figure 6.

In Figure 8, each tension bar *a*³ is divided at its ends and the two parts spread apart and their ends *f'* turned inwards to embrace the sides of the intermediate members *c*². In this figure, the tension bars of the corner pile or caisson *g* do not extend completely through the caisson but terminate therein with a cross or anchor piece *a*¹³ at the end. The remaining piles are in this figure indicated by the reference *b*⁵.

In all the constructions, each intermediate member extends the whole length of the piles as shown in Figure 10 or any desired portion of such length and serves to bind adjacent piles together so that they cannot separate but it does not prevent free relative longitudinal movements of the piles at its opposite sides.

In driving piles, each pile as it is driven into place has its tension members engaging successively the intermediate or interlocking member of the pile already driven and it carries down with it the intermediate member at its opposite side. If desired the driving blows may be applied to the intermediate member through a part which may permit a limited amount of relative longitudinal movement between pile and intermediate member. Thus in Figure 10, as the end pile *k* was driven, its tension members would successively engage in the recess in the intermediate member *c*² which had been driven into the ground with the pile *m*, and the intermediate member *c*¹² would be driven along with *k* so as to be ready for engagement by the tension members of the next pile. In some cases, the intermediate member of the pile which has already been driven, may be locked against endwise movement to its pile to prevent longitudinal displacement when the next pile is being driven. The tension rods are subjected chiefly to tensile stresses, the shearing or twisting stresses being insufficient to cause fracture of the concrete.

The intermediate or interlocking members in all the constructions may be left permanently in position, or they may be withdrawn after the several piles have been finally driven into place

and the space between adjacent piles filled in with concrete which keys itself into and around the ends of the tension members as shown in the lower portion of Figures 1-4.

5 The preferred way of concreting the spaces where the intermediate or interlocking members are located will be understood by reference more particularly to Figures 2 and 4. In these it will be seen that the intermediate or interlocking members c' or c^3 have a central hole n or n' formed longitudinally therethrough from end to end. As each member c' or c^3 is withdrawn, grout is fed down, if desired under pressure, the central hole n or n' so that it fills the space 10 beneath and around the lower end of the member. Thus the space between adjacent piles is gradually filled with concrete which constitutes an effective bond and key to hold the piles together in a secure and fluid-tight manner. If 15 desired a joist such as forms the interlocking member c^2 in Figure 3 may be lowered down into the grout or concrete in the space between the piles so as to take the place of the withdrawn special form of intermediate member with 20 the central hole n or n' , such as shown in Figures 2, 4 and 5.

The bottom of each intermediate or interlocking member may consist of a detachable shoe as shown at o in Figure 10 which remains in 30 position as the intermediate member is raised and concreting proceeds through the central hole n .

In some cases it may be desirable to flush, wash or blow out the spaces around the intermediate members in order to remove any slime, silt or 35 other material or soil which might interfere with efficient concreting. For this purpose the sides of the pile may as shown in Figure 5 be provided with recesses or channels p in their ends 40 adjacent to the intermediate members. Before concreting commences and if desired during driving, pipes conveying water or air under pressure are passed down the channels p to jet the walls of the pile and of the intermediate member clean 45 of silt, slime or the like. While jetting proceeds, grout may be fed or forced under pressure down the central hole n or n' and the intermediate member lifted so that the grout will not only 50 completely fill the space below the bottom of the intermediate member and between the piles but will flow up the channels p until it appears at the top of the pile which will be an indication that the passages are clear and that concreting 55 will proceed satisfactorily as the intermediate or interlocking member continues to be raised. The recesses or channels p may be provided in any desired parts of the end faces of the piles. If desired, grouting may be effected down the channels p after jetting.

60 The invention is not limited to any particular shape or configuration of pile or caisson. The several figures show various shapes suitable for different services and positions. For corner positions, a pile of cruciform shape may be used 65 with two sets of tension members at right angles to one another extending therethrough. Or the pile may be of plain shape with two sets of tension members at right angles to one another similar to the caisson arrangement shown in 70 Figure 8.

Concrete sheet piles can be interlocked with one another as shown and also with bearing or king poles or anchor piles which have tension members similar to those of the sheet piles.

75 In some cases the heads (which may, for ex-

ample, be of the shapes shown in Figures 1 and 2) which grip the intermediate or interlocking members may be secured to each pile at its opposite sides by bolt like members passing freely through transverse holes through the piles.

The present invention obviates the known defects of the interlocking means usually employed or which have been proposed for sheet piling and prevents damage to the concrete by the interlocking means during driving.

Where desired, instead of grouting with cement or concrete, we may use clay, bitumen or other material to suit any particular requirements.

In the appended claims the term "pile" is used to include bearing or king piles, anchor piles, sheet piles and caissons, to all of which this invention relates. The piles need not necessarily be driven downwards, but may be sunk by clearing a way in advance of their lower ends.

Having now described the invention, what is claimed as new and desired to secure by Letters Patent is:—

1. An interlocking reinforced concrete pile, a plurality of headed metallic tension members extending into the concrete of the pile and having heads projecting in spaced vertical alignment along at least one face of the said pile and adapted for sliding engagement with an interlocking member, and a metallic interlocking member adapted for sliding engagement with the said heads, a hole extending through the said interlocking member from end to end thereof.

2. An interlocking reinforced concrete pile, at least one groove formed in a face of said pile parallel to the axis of the pile, a series of headed metallic tension members extending into the concrete of the pile and having their heads projecting at intervals in vertical alignment into the said groove and adapted for sliding engagement with an interlocking member within the said groove and a metallic interlocking member adapted to enter the groove specified and to make sliding engagement with the specified heads of tension members within the said groove, a hole extending through the said interlocking member from end to end thereof.

3. An interlocking reinforced concrete pile, a plurality of vertically spaced metallic tension members extending through the said pile and having heads projecting at opposite sides thereof, the said heads at each side of the pile all lying in a vertical line with one another and being adapted for sliding engagement with an interlocking member.

4. An interlocking reinforced concrete pile, a plurality of vertically spaced straight metallic tension members free from projections within the pile extending through the concrete of the pile from side to side thereof and having shaped heads projecting from the concrete at the opposite sides thereof, the said heads at each side of the pile all lying in a vertical line with one another and being adapted for sliding engagement with an interlocking member but not with heads identical with those projecting at the other side of the pile.

5. A pile as claimed in claim 3 in which the sides of the piles from which the heads of the tension members project are formed with vertical grooves within which the said heads lie.

6. A pile as claimed in claim 3 in which the sides of the piles from which the heads of the tension members project have vertical grooves within which the said heads lie, the said heads

comprising end portions of the tension members extending at an angle from the main length of the tension members.

7. An interlocking reinforced concrete pile as claimed in claim 3 wherein the said tension members are arranged in pairs and connected together by horizontal strengthening and connecting pieces also embedded in the concrete.

8. A pile as claimed in claim 3 in which the 10 sides of the piles from which the heads of the tension members project have vertical grooves within which the said heads lie, the end portions of said tension members each comprising two 15 separate portions of the tension members extending apart from one another and then inwards towards each other at their extremities, the said extremities projecting through the walls of the grooves in the manner specified.

9. Interlocking reinforced concrete sheet piling 20 comprising a plurality of piles as claimed in claim 3 together with a plurality of metallic interlocking members disposed each between adjacent faces of two adjacent piles and slidably

engaging the heads of the tension members projecting from both the said adjacent faces and thereby interlocking the said piles together.

10. Interlocking reinforced concrete sheet piling comprising a plurality of vertically spaced metallic tension members extending through the said pile and having heads projecting at opposite sides thereof, the said heads at each side of the pile all being in a vertical line with one another and being adapted for sliding engagement with 10 an interlocking member, but not with heads identical with those projecting at the other side of the piles, and with a plurality of metallic interlocking members disposed each between adjacent faces of two adjacent piles and slidably 15 engaging the heads of the tension members projecting from both the said adjacent faces and thereby interlocking the said piles together. 5
